UNITED STATES PATENT OFFICE.

HENRY J. M. HOWARD, OF WASHINGTON, DISTRICT OF COLUMBIA.

WRENCH.

Application filed May 16, 1925. Serial No. 30,669.

This invention relates to wrenches in general and has for its principal object the provision of a wrench particularly applicable for use with fire prevention apparatus.

5 At the present time the use of fire hose cabinets is greatly increasing. In such devices the cabinet encloses the usual gate valve and the nipple in addition to the local or house fire hose hung in loops each supported 10 by transverse pivoted holders loosely mounted in the parallel arms of the hose rack so that the hose can be pulled out of the rack with extreme quickness.

After being used the hose should be dried 15 before being returned to the rack, this usually necessitating the removal of the coupling from the pipe nipple. And there are naturally other times when it is necessary to couple or uncouple this fitting, e. g., when the 20 metropolitan fire department desires to use their larger standard hose. When there is no rack or cabinet there is little difficulty in unscrewing the coupling but in the restricted space within the cabinet it is very difficult 25 to get at the two diametrically opposed lugs on the ring of the coupling and for this reason it has been proposed to increase the size of the cabinet or to have one side hinged. Both of these are highly disadvantageous 30 and I have therefore provided a special wrench making it possible to use the standard fittings and to use a rack fitting the pipe rather closely.

In the drawings:

35 Figure 1 is a top plan view of the wrench.
Figure 2 is a side elevation.

Figure 3 is a top plan view of a rack with the top removed showing the method of use of the wrench.

40 Referring particularly to Figure 3, 10 is a wall to which is affixed a cabinet 11, enclosing the gate valve (removed for clearness of illustration) and the usual rack supporting nipple, shown in cross section at 12. The 45 rotating ring 15 of the coupler which is detachably secured to the nipple 12, has integral, cylindrical, diametrically disposed lugs 16 by means of which the hose 17 supported in the rack 18 is disconnected from 50 the nipple 12.

The rack 18 is of well-known type being swiveled on the nipple 12 so that it can turn freely. The coupling end of the hose 17 is nearest the nipple 12 and the nozzle 20 of 55 this local fire hose is at the free end of the

rack, convenient of access as the rack is swung about its pivot on the nipple.

Referring now particularly to Figure 1, the wrench consists of a fairly long bar 22 serving as handle to both ends. On the one 60 end as 23, I prefer to provide projections 24 and 25 having their outer ends rounded and their inner ends curved, each cooperating with a triangular abutment 26 or 27, respectively, to grip between the projection 65 and the abutment the rim or other portion of a valve hand-wheel or disk so that the wrench may be used as a lever in opening or closing a valve having a hand-wheel.

The other end of the wrench, the one we 70 are particularly concerned with in this application, consists of an arcuate arm 30 having its concave surface 31 truly cylindrical and of such size and shape as to fit snugly the lugged ring of a hose coupling. 75 The convex surface 32 follows generally the same curve and merges with the bar-like handles 22 by means of a fillet 33. The arm 30 is provided with a plurality of openings 80 34, 35 and 36, the first of these being preferably at right angles to the axis of the bar or handle 22, the hole 36 being almost parallel to the length of the handle 22, and therefore in the handle portion itself, the mid-hole 35 being substantially between the 85 other two, and all three being cylindrical and of such size as to receive without undue lost motion one of the lugs of the ring of the hose coupling. It will be seen from Figure 1 that the three openings 34, 35, and 90 36 are radial, that is, if their axes are extended they would meet in a point which point would be the center of the inner arc of the arm.

The operation of the device can best be 95 understood from an inspection of Figure 3. It will be noted that the space available for manipulation of the wrench is very limited as the rack is above and the folds of the hose limit the movement toward the wall even when pushed back as far as it will 100 go and the wall 11 of the cabinet limits movement of the free end of the wrench in the opposite direction. No matter where the two lugs 16 are, however, one or the 105 other of them can always be reached by the hole 34, for example, as indicated in the figure. Turning the wrench clockwise as viewed in this figure we strike the edge of the wall 11 upon angular movement of about 110

30° and in so doing we have moved the opposite lug 16 to a point where it cannot be reached and we have come to a point where the hole 34 can no longer be utilized. We may, however, remove the wrench and catch the same lug 16 in one or the other of the holes 35 or 36 whichever is most convenient and we may again turn the ring thru a small angle and if necessary we may make a third and fourth turn; generally, however, three turns are ample to loosen the ring to an extent where the ring can be twirled by hand. In securing the hose back into place after it is dry the coupling is first turned by hand as far as it will go and then by a few turns of the wrench as just described it can be made perfectly snug, this not being possible with any wrench where the span between the holes is approximately a straight angle. If the holes were on opposite sides of the handle the purchase upon the ring would hardly be great enough to allow the proper manipulation of the tool but by having three holes all located to one side and by having the arcuate portion short, not over 120°, for example, a very convenient operation of the coupling is made possible.

What I claim is:—

1. In a wrench for operating the rotating ring of a fire hose coupler encased in a cabinet, a handle having an offset portion adapted to bear against the ring and having a plurality of holes therein to receive the lugs of the ring, one of said holes having its axis at an angle to the handle of less than 30°, a second hole having its axis spaced from the axis of the front or nearer hole by less than 45° and a third and most distant hole having its axis at less than 100° from the axis of the first hole.

2. The device of claim 1 in which the angle between the handle and the axis of the most distant hole is less than 100° and all three of the holes lie on the same side of the handle.

3. In a pipe wrench for use with fire prevention apparatus, an arcuate bar having three lug receiving holes therein within an angle of 90°, and having an integral handle making a slight angle with one of said holes so that said hole may be considered as in the handle portion.

In testimony whereof I affix my signature.

H. J. M. HOWARD.
